2,378,216

CONVERSION OF HYDROCARBONS

Vladimir Haensel and Bernard S. Friedman, Chicago, Ill., assignors to Universal Oil Products Company, Chicago, Ill., a corporation of Delaware

Application September 28, 1942, Serial No. 459,939

11 Claims. (Cl. 260—683.4)

This invention relates to the conversion of hydrocarbons and more particularly to a combination of interdependent and cooperative steps whereby a hydrocarbon mixture comprising essentially paraffins and olefins is separated into a second mixture of isoparaffins and olefins and this second mixture is subjected to alkylation to produce a saturated high antiknock distillate. This distillate is substantially saturated in character and is of high antiknock value. The major portion of this distillate boils within the range of gasoline and is particularly suitable for use in aviation gasoline.

In the alkylation of isoparaffins by olefins, it is essential that an excess of isoparaffins be present in the reaction zone in order to minimize undesirable polymerization reactions and also because the presence of an excess of isoparaffins has been found to yield alkylation products of higher antiknock properties. The ratio of isoparaffins to olefins is usually within the range of 3:1 to as high as 20:1 or, in certain cases, even higher.

In addition, experiments have shown that the presence of substantial amounts of normal paraffins in the alkylation zone has a deleterious effect upon the alkylation reaction. Further, the presence of such large amounts of normal paraffins increases the size of the alkylation equipment and thus adds considerably to the cost of alkylation plants. Also, this presence of large quantities of normal paraffins in the alkylation zone creates a heavy burden on the subsequent fractionation equipment of the process. In the alkylation processes heretofore proposed, the products from the alkylation zone comprise principally alkylate, normal paraffins and excess isoparaffins, and entails fractionation and distillation equipment of considerable expense in order to effect separation of these products. It is a particular feature of the present invention that this excessive cost of fractionation is greatly reduced by the combination of interdependent steps disclosed herein.

According to the present invention, the charging stock, comprising essentially a mixture of olefins and paraffins, is subjected to extraction in the presence of a particular separating agent which has been found to have a high capacity, that is, it will dissolve large proportions of the hydrocarbons and, in addition, it has a high selectivity—that is, it will dissolve the olefins preferentially to the paraffins. The extract phase, comprising principally the olefins and separating agent, is subjected to treatment with an isopar-

affin in order to release the olefins and to thereby produce a mixture of isoparaffin and olefins for the subsequent alkylation step of the process. Another particular feature of the present invention is that the quantity of olefins absorbed by the separating agent and the olefins released by contact with the isoparaffins are balanced to produce an isoparaffin-olefin mixture of the correct composition required for optimum alkylation.

These results are achieved by the use of the particular separating agent and the particular combination of interdependent steps disclosed herein.

In one specific embodiment the present invention comprises subjecting an olefin-paraffin mixture to extraction with a separating agent comprising essentially a phosphoric acid solution of silver phosphate, separating an extract phase from a raffinate phase, contacting the extract phase with an isoparaffin in order to separate an isoparaffin-olefin mixture in which the ratio of isoparaffins to olefin is within the range of 3:1 to 20:1, subjecting said isoparaffin-olefin mixture to alkylation in the presence of an alkylation catalyst, fractionating the products of said alkylation to separate a fraction comprising principally isobutane and recycling said fraction to the process.

The invention will be further explained in connection with the accompanying drawing which illustrates a flow diagram of one method in which the process may be conducted. However, it is not intended to limit the invention to the particular flow as shown in the drawing.

In order to simplify the further explanation of the invention the following description will be limited to the treatment of a butane-butylene charging stock. The butane-butylene fraction charged to the process will usually vary in its composition of normal butane, isobutane, normal butylene and isobutylene, as well as in the minor quantities of the lower and high boiling compounds, depending upon the source from which it is obtained and upon the method by which it is recovered. It is understood that the invention is not limited to the treatment of butane-butylene mixtures but that the invention is applicable to the treatment of other mixtures containing olefins and paraffins which are suitable, after treatment in the early stages of the present combination process, for alkylation in the subsequent stage of the process.

If the charging stock contains sulfur or sulfur compounds, the charging stock is preferably given a preliminary treatment in order to remove the sulfur therefrom. Usually a caustic wash will be

sufficient to remove the hydrogen sulfide but, if necessary, a more severe treatment may be employed.

Referring to the drawing, the charging stock is introduced to the process through line 1 and is directed into primary extractor or zone 2, which may be of any suitable type in order to effect the desired contact of the charge with the separating agent. Thus, this zone may take the form of one or more zones which may or may not contain packing material such as gravel, clay, synthetically prepared composites, etc., and/or fractionating means such as baffle plates, bubble trays or the like. In the particular case illustrated in the drawing, countercurrent flow of hydrocarbons and separating agent is shown, although it is understood that concurrent flow may also be utilized.

Referring again to the drawing, the separating agent may be introduced through line 3 to zone 2 and, after the operation of the process has commenced, the separating agent may comprise all or a portion thereof which is recycled within the process in a manner to be hereinafter described in detail.

The separating agent of the present invention comprises a phosphoric acid solution of silver phosphate. Experiments indicate the best results are obtained when employing high concentrations of silver phosphate. However, the concentration of the silver phosphate is limited by the concentration of the phosphoric acid. On the other hand, the concentration of the phosphoric acid is limited since the undiluted acid is too viscous and also since the undiluted acid tends to catalyze undesired reactions. Thus, for example, it has been found that phosphoric acid solutions of greater than 95 percent concentration are too viscous for practical use at ordinary temperatures. Therefore, according to the present invention, the phosphoric acid solution should be below 95 percent concentration and preferably below 90 percent concentration.

Effective separating agents have been prepared comprising 30 percent silver phosphate and 70 percent by weight of phosphoric acid of 85 percent concentration. Likewise, effective separating agents have been prepared comprising 18 percent silver phosphate and 82 percent by weight of phosphoric acid of 67.5 percent concentration. In general, it is preferred to utilize as high a concentration of the acid as is satisfactory in connection with the particular separation desired and also to use as high a concentration of the silver phosphate as may be dissolved therein. In most cases the concentration of phosphoric acid should be above 50 percent.

The silver phosphate-phosphoric acid solution may be prepared in any suitable manner. One convenient method is to mix the required amount of silver phosphate in a concentrated phosphoric acid solution and then add the necessary amount of water in order to yield a separating agent of the desired concentration. On the other hand the phosphoric acid may be diluted prior to the addition of the silver phosphate.

The temperature employed in primary extractor 2 will depend upon the particular compounds being treated and may range from sub-atmospheric up to 150° F., or more. In general the temperature should be below 150° F., in order to avoid undesired reactions which will occur at the higher temperatures. Although atmospheric, subatmospheric or superatmospheric pressures may be employed, it is generally preferred to em-

ploy sufficient superatmospheric pressure in order to maintain the hydrocarbons in substantially liquid phase.

5 The hydrocarbons and separating agent are then allowed to settle in either extractor 2 or in other zones into an extract phase and a raffinate phase. In multiple stage operations, the raffinate phase may be contacted with further quantities of the separating agent in order to finally recover substantially all of the olefins contained in the charging stock. The extract phases may then be combined and directed through line 4 into secondary extractor 5.

15 The raffinate phase or phases may be withdrawn from the upper portion of extractor 2 through line 6 and treated to separate the separating agent from the hydrocarbons. This may take any convenient form and the separating agent may be recycled, by well-known means not illustrated, to the extract step of the process. The saturated hydrocarbons are then directed into isobutane column 7 wherein they are fractionated in order to separate isobutane from normal butane. The normal butane is removed through line 25 8 to storage or any desired further treatment or use. The isobutane is removed through line 9 and a portion thereof may be withdrawn from the process, while all or at least the remaining portion is directed through line 10 into secondary extractor 5. Line 11 is provided for the introduction of additional isobutane, if required.

30 Secondary extractor 5 is usually operated within the same range of conditions heretofore specified in connection with primary extractor 2, that is, temperatures of below about 150° F., and sufficient superatmospheric pressure to maintain the hydrocarbons in substantially liquid phase. It is believed that a complex is formed between the olefins and the separating agent and that this 35 complex is in equilibrium in the extract phase. By contacting the isoparaffins with the extract phase, this equilibrium is disturbed and the olefins are released from the solution in order to maintain the new equilibrium established. Thus, a very effective and ready separation of the olefins is accomplished in an improved manner.

40 The use of isobutane or other isoparaffins which are to be subsequently alkylated as the stripping medium in this step of the process, is of prime importance since it eliminates any further fractionation of the mixture of isoparaffin and olefin, and this is one of the particular features of the present invention.

45 Another important advantage of this method of operation is that it eliminates the necessity of heating the extract phase to high temperatures in order to separate the olefins. Heating to high temperatures may cause polymerization or hydration reactions which are undesired in the particular process of the present invention.

50 The silver phosphate-phosphoric acid solution is removed from extractor 5 through line 12 and all or a portion thereof may be withdrawn from the process. Preferably, however, the greater portion of this solution is recycled by way of lines 12, 13 and 3 to extractor 2 for further use in the process.

55 The isobutane-olefin mixture is withdrawn through line 14 from the upper portion of extractor 5 and, as a particular feature of the present invention, this stream has a composition of isoparaffin to olefin within the range of 3:1 to 20:1 and in most cases the ratio of isoparaffin to olefin will be within the range of 5:1 to 10:1.

This stream is then directed through line 14 into alkylation zone 15.

Alkylation zone 15 may comprise any of the well-known forms of alkylation equipment suitable for obtaining intimate contact between the hydrocarbon reactants and the alkylation catalyst under controlled conditions of temperature, pressure and time of contact. Any suitable alkylation catalyst may be employed, the preferred catalysts being hydrogen fluoride, sulfuric acid and phosphoric acid, although these catalysts are not necessarily equivalent in their activity in effecting the desired reaction. Under certain circumstances, metal halides and particularly aluminum chloride may be utilized as the catalyst. The present invention is not limited to any particular catalyst and, even in certain cases, where it is desired to effect the reaction by purely thermal means, the catalyst may be omitted. Although not illustrated in the drawing, when a mineral acid catalyst in liquid condition is employed, suitable means will, of course, be provided for the introduction and withdrawal of the catalyst. Likewise, it is within the scope of the invention to recycle all or a portion of the catalyst within the alkylation zone or to regenerate the catalyst prior to such recycle.

The exact temperature and pressure to be employed in the alkylation reaction will, of course, depend upon the catalyst. When utilizing hydrogen fluoride catalysts, the temperatures employed are usually within the range of about 50° F., to about 200° F., and preferably between about 60° F., to about 125° F. Usually sufficient pressure is employed to maintain the reactants in liquid phase, although it is within the scope of the invention to utilize vapor or mixed phase operations when desired.

The alkylation products are directed through line 16 into debutanizing column 17. As a particular feature of the present invention, the products being introduced into zone 17 will comprise principally alkylate and excess isobutane. Thus, a simple debutanizing operation will effect the desired operation in order to evolve and remove the isobutane from the liquid alkylate. In contrast, in the absence of the features of the present invention, the products from the usual alkylation process contains varying proportions of normal butane in addition to the isobutane and alkylate. This then requires rather expensive fractionating equipment for accomplishing the desired separation.

The liquid alkylate is withdrawn from zone 17 through line 18 and usually will be rerun in a separate zone to effect the recovering of gasoline or gasoline fractions of the desired end boiling point.

The separated isobutane is withdrawn from the upper portion of the zone 17 and all or a portion thereof may be removed from the process through line 19. Preferably, however, at least a portion of the isobutane will be recycled to the alkylation step by way of lines 20 and 21. In case other components are present in sufficient quantity in the isobutane stream withdrawn from zone 17, it is within the scope of the invention to direct all or a portion of this stream through lines 22 and 6 into isobutane column 7. Likewise, when desired, all or a portion of the isobutane stream may be directed through lines 20 and 10 to secondary extractor 5.

The following example is introduced for the purpose of further illustrating the nature of the invention and is not intended to unduly limit the same.

A butane-butylene fraction containing 20 percent of butylenes is subjected to extraction at a temperature of about 100° F., with a separating agent comprising 30 percent by weight of 5 silver phosphate and 70 percent by weight of 85 percent phosphoric acid. The extract phase is then contacted with isobutane sufficient to separate most of the dissolved olefin and to yield an isoparaffin-olefin mixture in which the ratio of isobutane to olefin is 10:1. The isoparaffin-olefin mixture is then subjected to alkylation at a temperature of about 100° F., in the presence of hydrogen fluoride catalyst. The products are fractionated to separate alkylate from isobutane, a portion of the isobutane being recycled to the isobutane column and the remaining portion being supplied to the secondary extractor. The alkylate is further fractionated to separate a fraction having a 300° F. end boiling point and this latter fraction is of high antiknock value and particularly suitable for use in aviation gasoline.

We claim as our invention:

1. A process for preparing an isoparaffin-olefin fraction relatively free of normal paraffin, which comprises contacting a hydrocarbon fraction containing olefins and normal and isoparaffins with a phosphoric acid solution of silver phosphate under conditions such that there is formed an olefin

25 extract phase containing said solution and said olefins in the proportion at least approaching that of an equilibrium mixture of the two components, separating the extract phase from the paraffin or raffinate phase and contacting an isoparaffin with said extract phase under conditions such that equilibrium in the extract phase is disturbed and the olefins released therefrom.

2. The process defined in claim 1 further characterized in that the amount of isoparaffin contacted with said extract phase is in excess of the normal and isoparaffin content of said hydrocarbon fraction.

3. A process for preparing an isoparaffin-olefin fraction relatively free of normal paraffin, which 45 comprises contacting a hydrocarbon fraction containing olefins and normal and isoparaffins with a phosphoric acid solution of silver phosphate under conditions such that there is formed an olefin extract phase containing said solution and said olefins in the proportion at least approaching that of an equilibrium mixture of the two components, separating the extract phase from the paraffin or raffinate phase, separating said 50 raffinate phase into a normal paraffin part and an isoparaffin part and contacting an isoparaffin 55 including the isoparaffin separated from the raffinate phase with said extract phase under conditions such that equilibrium in the extract phase is disturbed and the olefins released therefrom.

4. A process for preparing an isobutane-butene fraction relatively free of normal butane which 60 comprises contacting a C₄ hydrocarbon fraction containing butenes and normal and isobutanes with a phosphoric acid solution of silver phosphate under conditions such that there is formed a butene extract phase containing said solution and said butenes in the proportion at least approaching that of an equilibrium mixture of the two components, separating the extract phase from the butane or raffinate phase and contacting an isobutane with said extract phase under conditions such that equilibrium in the extract phase is disturbed and the olefins released therefrom.

5. A process for preparing an isobutane-butene 75 fraction relatively free of normal butane which

comprises contacting a C₄ hydrocarbon fraction containing butenes and normal and isobutanes with a phosphoric acid solution of silver phosphate under conditions such that there is formed a butene extract phase containing said solution and said butenes in the proportion at least approaching that of an equilibrium mixture of the two components, separating the extract phase from the butane or raffinate phase, separating said raffinate phase into a normal butane part and an isobutane part and contacting isobutane including that separated from said raffinate phase with said extract phase under conditions such that equilibrium in the extract phase is disturbed and the olefins released therefrom.

6. The process defined in claim 5 further characterized in that the amount of isobutane contacted with said extract phase is in excess of the amount of normal and isobutane in said C₄ fraction.

7. A process for preparing an isobutane-butene fraction relatively free of normal butane, which comprises contacting a C₄ hydrocarbon fraction containing butenes and normal and isobutanes with a phosphoric acid solution of silver phosphate, at a temperature below about 150° F. and under a superatmospheric pressure sufficient to maintain the C₄ hydrocarbons in substantially liquid phase, thereby forming an extract phase containing butenes and said solution in the proportion at least approaching that of an equilibrium mixture of the two components, separating the extract phase from the butane or raffinate phase, separating said raffinate phase into a normal butane part and an isobutane part and extracting the butenes from said extract phase at a temperature below about 150° F. by contacting therewith isobutane including isobutane from said raffinate phase, in sufficient amount to disturb the equilibrium in the extract phase and release the butenes therefrom.

8. A process which comprises contacting a C₄ hydrocarbon fraction containing butenes and normal and isobutanes with a phosphoric acid solution of silver phosphate under conditions such that there is formed a butene extract phase con-

taining said solution and said butenes in the proportion at least approaching that of an equilibrium mixture of the two components, separating the extract phase from the butane or raffinate phase, stripping the butenes from said extract phase by contacting therewith isobutane including that separated from said raffinate phase in an amount sufficient to disturb the equilibrium in the extract phase and release the butenes therefrom, subjecting the resultant isobutane-butene fraction to alkylation in the presence of an alkylating catalyst different in composition than the silver phosphate solution, separating unreacted isobutane from the products of alkylation and returning the isobutane thus separated to the olefin stripping step.

9. A process for preparing an isoparaffin-olefin fraction relatively free of normal paraffin which comprises contacting a hydrocarbon fraction containing olefins and normal and isoparaffins with a phosphoric acid solution of silver phosphate under conditions such that olefins are absorbed in the extract phase, separating the resultant extract phase from the raffinate phase and contacting an isoparaffin fraction relatively free of normal paraffins with said extract phase to extract olefins from the latter.

10. A process for preparing an isoparaffin-olefin fraction relatively free of normal paraffin which comprises contacting a hydrocarbon fraction containing olefins and normal and isoparaffins with a phosphoric acid solution of silver phosphate under conditions such that olefins are absorbed in the extract phase, separating the resultant extract phase from the raffinate phase, separating said raffinate phase into an isoparaffin part and a normal paraffin part and contacting said isoparaffin part with said extract phase to extract olefins from the latter.

11. The process of claim 10 further characterized in that said hydrocarbon fraction comprises a C₄ hydrocarbon fraction consisting essentially of butenes, isobutane and normal butane.

VLADIMIR HAENSEL,
BERNARD S. FRIEDMAN.
